Attorney.

UNITED STATES PATENT OFFICE.

JAMES RAMSFORD FREELAND, OF WELLSVILLE, NEW YORK, ASSIGNOR OF ONE-HALF TO EDWIN COLTON BRADLEY, OF SAME PLACE.

SINGLETREE.

SPECIFICATION forming part of Letters Patent No. 383,351, dated May 22, 1888.

Application filed February 7, 1888. Serial No. 263,919. (No model.)

To all whom it may concern.

Be it known that I, JAMES RAMSFORD FREELAND, a citizen of the United States, residing at Wellsville, in the county of Allegany and State of New York, have invented certain new and useful Improvements in Singletrees; and I do hereby declare that the following is a full, clear, and exact description of the invention, which will enable others skilled in the art to 5 know which it appertains to make and use the same, reference being had to the accompanying drawings, which form a part of this specification, and in which—

Figure 1 is a perspective view of so much of 15 a running-gear of a vehicle as is necessary to illustrate my invention. Fig. 2 is a perspective detail view of my improved device. Fig. 3 is a plan or top view of the same; and Fig. 4 is a vertical cross-section on line x x , Fig. 3. 20 Like letters of reference denote corresponding parts in the several figures.

My invention relates to regulating devices 25 for the singletrees of buggies and all other kinds of vehicles using singletrees instead of doubletrees; but it is also adapted to be used in connection with the attachment of the singletrees to a doubletree.

The object of my invention is to construct 30 a regulating device whereby the play of the singletree upon the bolt by means of which it is attached either to the pole or to the doubletree, as the case may be, may be regulated, substantially in the same manner and for the same purpose as described in the specification 35 relating to my improvement in doubletrees for which Letters Patent of the United States, No. 374,468, were issued to me under date of December 6, 1887.

The nature of this improvement in its application to singletrees will readily be understood by reference to the accompanying drawings, in which the letter A designates one end of a doubletree, through which a bolt, B, is inserted, and upon this bolt the singletree 45 (shown at C) is pivoted in such a manner that it may turn freely. In order to prevent wear or undue chafing of the upper part of the doubletree and the under side of the singletree, both of these are provided with chafing

or friction plates, as shown at a and c, respectively.

The letter D designates a bail, made of suitable metal, and having an enlarged part, d, at its upper end, through which the pivot-bolt B is inserted. At its lower end this bail 55 terminates in a plate, E, which may be fastened to the under side of the doubletree by means of bolts, screws, or in any other suitable manner. The nut F of the bolt bears 60 against this plate E.

The singletree is provided with a rearwardly-projecting bail or segment, G, the opposite ends of which may conveniently be fastened in plate c, or they may be fastened in the body of the singletree in any desired manner. This bail or segment, which, in conjunction with the bail-piece D, forms the regulating device, is provided with two shoulders or offsets, g g, on opposite sides of the vertical bail-piece D. The latter is provided on its 70 inner side with an offset, H, having a groove or recess, h, in which the middle part of the segment G is free to play between its shoulders g g; but it will be seen that the offset H forms a stop or limit to the play of the segment, which is controlled by said shoulders g g striking against opposite sides of the offset H. It will also be seen that this offset will prevent the singletree from doubling or turning upon the doubletree so as to strain 75 the pivot-bolt, and in this manner it will be seen that the play of the singletree is limited not only in a horizontal plane by means of the shoulders g g and the offset H, but also in a vertical plane by the bail or segment G 80 bearing against the under side of the said offset H, thus relieving the bolt from undue strain and preventing it from becoming strained, bent, or distorted.

It will readily be observed that a construction, arrangement, and operation of my device is precisely the same, whether the singletree be attached to a doubletree, as in Fig. 2, or to the pole of a buggy or other vehicle using but a single horse, as in Fig. 1. In the latter case the bail D is simply fastened at its lower end upon the pole, its upper end engaging 95 the top of a pivot-bolt, which is inserted

through the pole, and upon which the single-tree swings and draws.

Having thus described my invention, I claim and desire to secure by Letters Patent of the 5 United States—

The combination of the singletree provided with a rearwardly-projecting bail or segment having two stops or offsets, the bolt upon which the singletree is pivoted and on which 10 it draws, and the rearwardly-projecting bail or segment fastened at opposite ends to opposite ends of the bolt, and provided with an

offset or shoulder overlapping and adapted to engage the shoulders on the rearwardly-projecting bail, substantially as and for the purpose shown and set forth. 15

In testimony that I claim the foregoing as my own I have hereunto affixed my signature in presence of two witnesses.

JAMES RAMSFORD FREELAND.
